UNITED STATES PATENT OFFICE

RALPH V. L. HARTLEY, OF SOUTH ORANGE, NEW JERSEY, ASSIGNOR, BY MESNE ASSIGNMENTS, TO WESTERN ELECTRIC COMPANY, INCORPORATED, A CORPORATION OF NEW YORK

SOUND RADIATOR

Application filed March 31, 1925. Serial No. 19,746.

This invention relates to a sound radiator designed to act directly on the air and impart vibrations to the air from a relatively large surface.

- 5 An object of this invention is to provide a vibratile member so shaped as to make vibration equally possible for all frequencies throughout the important frequency range in speech and music.
- 10 A further object is to provide a vibrating system which offers to the air a low mechanical impedance comparable with that of the air and to the mechanical driving member a higher impedance comparable with 15 that of the driving means, thereby obtaining a system which faithfully imparts a large portion of the vibratory energy to the air.

In general, this invention comprises a 20 sound radiator of light weight material in the form of a plane surface, or its structural equivalent, having one edge driven perpendicular to itself and a non-parallel opposite edge attached to a fixed support.

25 The vibrating surface and the driving system are designed to make vibration substantially equally possible for all frequencies throughout the sound range and thus obtain uniform response and uniform impedance.

A specific application of this invention, more fully hereinafter described, comprises its application to a loud speaking receiver in the form of a plane surface or its structural equivalent having a trapezoidal or similar shaped sound radiator in which one non-parallel edge is attached to a torsional driving member so that torsional motion of this driving member imparts vibrational 35 motion perpendicular to the surface of the sound radiator and the non-parallel edge opposite the torsional driving member is rigidly supported. The driving member 40 may vibrate the sound radiator perpendicular to itself by having a transverse motion instead of a torsional motion. The motor element should preferably be attached to the torsional drive at the high frequency end, that is, the end where the sound radiator is narrowest.

Referring to the drawings, Fig. 1 is a general assembly side view of the sound radiator with supporting means and motor element. Fig. 2 is an end view looking towards the sound radiator and showing 55 the motor element. Fig. 3 is a side view of a plane sheet sound radiator of somewhat different shape from that shown in Fig. 1. Fig. 4 is an end view of the plane sound radiator showing the attachment of 60 the fixed and the vibratile edges. Fig. 5 is a side view of a hollow stiffened sound radiator. Fig. 6 is an end view of Fig. 5. Fig. 7 is a side view of a hollow stiffened sound radiator having its edges shaped 65 similar to Fig. 3. Fig. 8 is an end view of Fig. 7.

In Fig. 1, the base plate and main supports for the mechanism are shown at 10, 11, 12 and 13. 14 is the sound radiator made 70 of light weight material and is attached to the vibrating member 15 at one edge by means of the clamp 16 and at its opposite edge to the non-parallel rigid support 18 by means of the clamp 17. The vibrating 75 member 15 is supported at each end by means of knife edges or other suitable anti-friction bearings 19 and 20. The fixed support 18 for the sound radiator is capable of being adjusted to permit the sound radiator 14 being placed under a greater or lesser tension. This adjustment is made and fixed 80 by bolts 21, 22 and 23, which permit the sound radiator to be placed under tension, and to evenly take up the tension particularly when the adjustment is made by the screw 21 only. Screws 22 and 23 permit locking the member 18 in the position it takes when adjustment is first made by screw 21, and also permits placing a greater 85 tension on one end of the sound radiator than on the other. 24 is the motor element, consisting of any suitable driving means, such as shown in Egerton Patent No. 1,365,898 dated January 18, 1921, suitably 90 supported and connected to the sound radiator. The connection is such that vibration of the armature of the motor produces a torsional vibrational movement of the shaft 95 or rod 15 which is attached to the driven 100

edge of the sound radiator 14 in such a manner that torsional vibration 15 imparts a vibrational motion to 14 perpendicular to its surface.

5 Fig. 2 is an end view of the motor element 24 and shows a means consisting of members 26, 27, 28 and 29 for connecting the motor element to the driving member 15 so that vibration of the armature 25 is imparted to the sound radiator through torsional vibration of the driving member 15.

Fig. 3 shows a side view of a modified shape of the sound radiator 30 in which the change in distance from the driven edge to the fixed edge as one end is approached does not change in proportion to the distance along the radiator, as in the case of a trapezoidal shaped sound radiator shown in Fig. 1. Curving the edge of the sound radiator 20 opposite the driven edge, permits distributing the frequency absorption for different frequencies along the diaphragm in accordance with any desired plan, that is, the dimension of the diaphragm normal to the driven edge may be made to increase uniformly with frequency throughout the entire length of the diaphragm or it may be made to increase at a greater or lesser rate than uniformly.

30 Fig. 4 is an end view of a flat sound radiator showing particularly the clamps 16 and 17 attached to its vibratile and fixed edges, respectively. This or similar methods of supporting the sound radiator in any of its forms may be used.

35 Fig. 5 is a side view of a trapezoidal shaped hollow sound radiator 31 stiffened primarily by means of trussing. Fig. 6 is an end view of Fig. 5 showing primarily the cross section and center expansion member 32 between the two faces.

40 Figs. 7 and 8 show a sound radiator 33 similar to Figs. 5 and 6 respectively, with the exception that one edge is curved.

45 When a single flat sheet sound radiator is used such as shown in Figs. 1 and 3, it is held taut or under any desired tension by the means provided for this purpose. The sound radiators shown in Figs. 5 and 50 7 are of such design that they are self-supporting and may or may not be placed under static stress by the supporting members 15 and 18.

55 The sound radiator may be made preferably of parchment paper, a good grade of drawing paper, blotting paper, fabric material, or other light weight material, such as aluminum.

60 The width of the sound radiator at the narrow end should be approximately one-half the wave length for the high frequency and at the wider end approximately one-half the wave length for the low frequency.

65 For the higher frequencies the narrower portion of the sound radiator at the left

will absorb and radiate to the air most of the vibrational energy while for somewhat lower frequencies the vibrations will spread over the sound radiator towards the wider edge at the right and an area dependent on the frequency will be set into resonant vibration. The relatively high mechanical impedance due to this motion will be effectively in series with that of the remainder of the rod, and so a large share of the energy will go into the sound radiator. For the lower frequencies the sound radiator impedance will be low and the energy will be transmitted along the rod to a point where owing to the increased width of the sound radiator, resonance is possible at that frequency. The energy will then pass over into the sound radiator and be radiated to the air. The lower frequency limit of such a system would be determined by its size. As the velocity of sound in the driving member 15 may be made much greater than that of the sound radiator made of such material as paper, the distribution of the various components along this structure would not introduce any appreciable distortion due to the lower frequencies being retarded.

It will be obvious that the driving member 15 can be given translatory movement instead of rotary movement to drive the sound radiator if desired. It will further be obvious that the motor elements may be placed at both ends of the driving member 15 when this may be found desirable.

It will be apparent to those skilled in the art that various other modifications of the invention may be made and that the invention is not therefore limited to the specific structures that have been illustrated but its scope is defined in the appended claims.

What is claimed is:

1. A large direct-acting sound radiator of light weight material, means for tensioning said radiator, and means for driving said sound radiator at substantially every point along an edge thereof.

2. A large direct-acting sound radiator of light weight material having the greater portion of one edge attached to a fixed support and the greater portion of the opposite edge attached to a vibratile support.

3. A large direct-acting sound radiator of light weight material having a vibratile edge, and means for driving the vibratile edge at substantially all points simultaneously in a direction perpendicular to the surface of the sound radiator.

4. A large direct-acting sound radiator consisting of a vibratile member having one edge attached at substantially all points to a fixed support and an opposite non-parallel edge attached at substantially all points to a vibratile support.

5. A large direct-acting sound radiator

- consisting of a vibratile member of light weight material having a vibratile edge and a non-parallel opposite fixed edge, and means for varying the tension in the vibratile member.
6. A large direct-acting sound radiator, means for imparting vibrational forces simultaneously to all points along an edge of said radiator, and means for varying the static tension in said sound radiator.
7. A large direct-acting sound radiator consisting of a sound radiating member having a straight vibratile edge, and rotary means for driving the vibratile edge at substantially all points in a direction perpendicular to the surface of the sound radiator.
8. A direct-acting sound radiator consisting of two sheets of thin material, means for securing said sheets along one edge and means for imparting vibrations to another edge, said sheets being fastened together at their driven edge and at their fixed edge, and a separating member for holding said sheets apart along a line between said edges.
9. A large direct-acting sound radiator, means for tensioning said radiator and means for clamping two opposite edges of said sound radiator, one of said clamping means being fixed and the other of said clamping means being vibratile to vibrate the said sound radiator in accordance with sound waves, each of said clamping means extending the full length of the edges clamped thereby.
10. In combination, a driving member, a large direct-acting sound radiator consisting of a vibratile member having two of its opposite edges non-parallel, one of said edges being attached to a fixed support, and a vibratile support connected in operative relation with said driving member and attached to another edge of said sound radiator.
11. In combination, a driving member, a large direct-acting sound radiator consisting of two sheets of thin material, means for securing said sheets along one edge, means for imparting vibrations to another edge, said sheets being fastened together at their driven edge and at their fixed edge, and a separating member for holding said sheets apart along a line between said edges, the driven edge of said sound radiator being connected in operative relation with said driving member.
12. A large direct-acting sound radiator comprising a vibratile member having one edge attached to a driving member and the opposite edge attached to a fixed support, the distance between the fixed support and the driving member increasing progressively along the length of said sound radiator.
13. A direct-acting sound radiator of light weight material comprising a vibratile member of variable width, the distance between the fixed edge and the driven edge being a non-linear function of the distance from either end of the sound radiator.
14. An acoustic device comprising a large direct acting sound reproducing means and an actuating device therefor including a rotary means, both of said means being joined throughout the greater portion of their lengths.
15. An acoustic device comprising a large direct acting diaphragm and actuating means therefor including a long rotary element driving said diaphragm at substantially every point along a straight line between two edges of said diaphragm.
16. An acoustic device comprising a large direct acting diaphragm and actuating means therefor including a long rotary element driving said diaphragm along a straight line extending the greater part of the distance between two edges of said diaphragm.
17. An acoustic device comprising a large direct acting diaphragm and actuating means therefor including a rotary member substantially the length of one dimension of said diaphragm and connected thereto at every point along one element between two opposite edges of said diaphragm.
18. An acoustic device comprising a large direct acting diaphragm and actuating means therefor including a rotary member approximately the length of one dimension of the diaphragm and means connecting all points along a longitudinal element of said member to said diaphragm and between two opposite edges of said diaphragm.
19. An acoustic device comprising a tensioned sound radiator, a member rigidly secured to said radiator across one dimension thereof, and means for imparting vibrational forces simultaneously to all portions of said member.
20. A loud speaking diaphragm consisting of a plane sheet of metal having a density substantially that of aluminum supported at two opposite ends only and held under tension along its vibratory surface.
21. A loud speaking diaphragm consisting of a plane sheet of metal having a specific gravity greater than 2.7 and less than 3 supported at two opposite ends only and held under tension along its vibratory surface.
22. A direct acting diaphragm of loud speaking area comprising a quadrilateral plane sheet of thin flexible material held permanently in a stretched condition along its vibratory surface.
23. A direct acting diaphragm of loud speaking area comprising a quadrilateral plane sheet of thin flexible metal supported at two opposite ends only and held permanently stretched along its vibratory surface.
24. An acoustic diaphragm of loud speak-

ing area having a length equal to at least twice its width and means for tensioning said diaphragm in the direction of one dimension only.

16 25. An acoustic diaphragm of loud speaking area comprising a quadrilateral sheet of metal having a specific gravity greater than 2.7 and less than 3 tensioned in the direction of its length only, the length of said sheet being not less than twice its width.

17 In witness whereof, I hereunto subscribe my name this 27th day of March, A. D. 1925.
